UNITED STATES PATENT OFFICE.

ROBERT W. SCOTT, OF PHILADELPHIA, PENNSYLVANIA, ASSIGNOR OF ONE-HALF TO LOUIS N. D. WILLIAMS, OF ASHBOURNE, PENNSYLVANIA.

RIB-KNITTING MACHINE.

SPECIFICATION forming part of Letters Patent No. 577,789, dated February 23, 1897.

Application filed May 8, 1896. Serial No. 590,703. (No model.)

To all whom it may concern:

Be it known that I, ROBERT W. SCOTT, a citizen of the United States, residing in Philadelphia, Pennsylvania, have invented certain 5 Improvements in Rib-Knitting Machines, of which the following is a specification.

The object of my invention is to so construct a rib-knitting machine as to provide for the application of a facing or lining weft 10 to one face of the fabric which is being produced, and this object I attain in the manner hereinafter set forth, reference being had to the accompanying drawings, in which—

Figure 1 is a vertical section of sufficient of 15 a rib-knitting machine to illustrate my invention. Fig. 2 is a plan view of the same with parts cut away in order to bring it within the dimensions of the sheet. Fig. 3 is an inverted plan view of the dial cam-plate and 20 its cams. Fig. 4 is a plan view showing a dial cam-plate with a modified arrangement of cams whereby jacks are dispensed with. Figs. 5 and 6 are sections respectively on 25 the lines 5 and 6, Fig. 4, and showing the needle-dial and needles; and Fig. 7 is a sectional diagram showing a modified arrangement of needle-carriers.

In Fig. 1, A represents part of the fixed annular bed of the machine, to which is suitably 30 secured the needle-cylinder B, the latter having the usual vertical guides for the reception of the cylinder-needles.

D is the usual cam-cylinder surrounding the needle-cylinder, and F is the dial cam-plate, which is secured to and rotates with a 35 central spindle F', which may have any desired structural connection with the rotating device which actuates the cam-cylinder D, so that said cam-cylinder and dial cam-plate rotate in unison.

G is the needle-dial, radially grooved, as usual, for the reception of the needles a, these grooves, however, being extended inwardly, so as to provide for the reception of two sets 45 of jacks d and f, which are alternated throughout the dial G. The jacks d are shorter than the jacks f and have bits projecting into an annular camway d', formed in the cam-plate F, the jacks f having bits extending into an 50 annular camway f' in said cam-plate. The cam-plate F has two sets of knitting-cams,

these comprising, as usual, the projecting-cam g, the guard-cam g', and the retracting-cam g'', and it also has two other cams d'' and f'', the cam d'' occupying the camway d' 55 and the cam f'' occupying the camway f', as shown in Fig. 3. On the cam-plate F are also a pair of cams h and i, and mounted upon said cam-plate are diametrically-opposed plates I and J, projecting radially outward from the cam-plate and each having on the under side cams m and n.

Mounted upon the needle-cylinder B is a ring K, in the upper face of which are grooves which form radial continuations of the 65 grooves of the dial G, and in these grooves are guided jacks s, adapted to be controlled by the cams of the plates I and J.

Each of the cams h and i has a nose t, perforated, so as to serve as a weft-thread guide, 70 and the inner portion of each cam terminates in a tail, serving to retract to the full extent the dial-needles which come under its action.

The operation of the machine is as follows: 75 Supposing that the cam-plate F is being rotated in the direction of the arrows, Fig. 2, one-half of the needles will be projected by the jacks d under the action of the cam d' until the bits of said needles are brought under 80 the influence of the outer face of the cam i, which will continue to project the needles, the latter entering the grooves of the ring K and the movement continuing until the needles reach the position shown at the right-hand side of Fig. 1. When in this position, the weft-thread passing through the perforated nose t of the cam i can be fed in behind the bits of the projected needles. Hence 85 when the latter are again thrust inward by the action of the jacks s under the influence of the cam m of the plate J they will pass over said weft-thread, which will consequently be laid between the stitches of the dial-needles which were not projected and the stitches of 90 the needles which were projected. As soon as the jacks s have performed their duty of restoring the needles to the grooves of the dial said jacks are retracted by the cam n of the plate J. Hence when the dial-needles 95 reach the knitting-cams g g' g'' in the rear of said plate J all of the dial-needles can be pro-

jected by said knitting-cams, so as to receive the knitting-thread and form stitches, and when the stitches which were on the dial-needles have been cast off the weft-thread will 5 lie alternately under and over said stitches and behind the stitches of the cylinder-needles. While these operations are being performed by the cam d^2 , jacks d , cam i , jacks s , and cams m and n of the plate J upon one- 10 half of the needles the alternate needles are being acted upon in like manner by the jacks f , cam h , jacks s , and cams m and n of the cam-plate I preparatory to the formation of stitches upon all of the dial-needles by the 15 action of the second set of knitting-cams in the rear of said plate I . Hence in forming one course of stitches the weft-thread will be laid under the stitches of certain needles of the dial, say the needles 1 3 5 7, &c., and over 20 the stitches of the alternate needles 2 4 6 8, &c., of said dial, while in the next course the conditions are reversed, the weft-thread being laid over the stitches of the needles 1 3 5 7, &c., and under the stitches of the needles 2 25 4 6 8, &c. This operation results in the formation of a fabric such as shown in application for patent filed by me on the 5th day of May, 1896, Serial No. 590,296.

The tail v of the cam h or i serves to retract 30 to the full extent the non-projected needles, thus drawing up the stitches carried thereby and slackening the stitches on the projected needles, so as to relieve the latter from excessive strain.

35 When the machine employed is but a single-feed machine, but one set of projecting jacks, one needle-projecting cam, and one cam-plate with its needle-restoring jacks need be used, the weft-thread in this case 40 being tied in at the same wales of the fabric in each course of the knitting. If desired, the jacks may be entirely dispensed with and the needles actuated directly by the cams on the cam-plate F . Such a construction is shown in Fig. 4, in which g , g' , g^2 , h , and i represent cams similar to and having the same functions as the correspondingly-lettered cams in Figs. 1, 2, and 3. Every other one of the dial-needles in this machine, 45 however, has a bit longer than that of the needle beside it, (see Figs. 5 and 6,) and there are on the cam-plate F two cams w and w' , adapted to act upon the long bits only, the short bits passing beneath the same, the cam 50 w being a push-outcam and the cam w' a push-in cam.

When the cam h is approaching the needles, the cam w acts in advance of said cam h and pushes out the long-bitted needles until their 55 bits are in range of said cam h , so that only these long-bitted needles will be projected by the latter, the short bits passing behind said cam h and the projected needles, after the weft-thread has been laid behind the same, being retracted by means of a cam m' on the cam-plate F , so as to bring their bits within range of the approaching set of knitting-

cams, which thus act upon all of the needles. The final cam of this set projects all of the needles to such an extent that their bits are 70 within range of the approaching projecting-cam i , but in advance of the latter is the cam w' for depressing the long-bitted needles. Hence only the short-bitted needles are acted upon by said cam i , the long bits passing behind the same, and the short-bitted needles, after the weft-thread has been laid behind the same, being drawn in by the cam m^2 , so as to be within range of the next set of knitting-cams, which leaves the needles in condition 75 for the long-bitted needles to be again projected by the cam w .

The weft-thread guide t may, as will be evident, be independent of the cam h or i , as desired, the construction shown being preferred simply because of its convenience.

I have shown my invention as employed in connection with a circular-knitting machine, but the invention can be adopted as well in straight-knitting machines. Hence in some 90 of the claims I have used the term "needle-carrier" to indicate a circular dial or straight bed.

It is not necessary that the two needle-carriers should be at an angle to each other, as 95 they may, if desired, be in line with each other, as shown, for instance, in Fig. 7, one needle-carrier having, in addition to its own needle-grooves, additional grooves for receiving and guiding the needles projected from 100 the other carrier.

Of course it will be understood that the needles may be arranged in alternating sets or groups of any desired number each, so that a number of needles in succession may be projected or allowed to remain in the retracted position, depending upon the desired length of the "floats" or "ties" of the weft-thread. It will be apparent also that in a multiple-feed machine the needles may be projected 105 in advance of successive sets of knitting-cams, so that the weft-threads will be tied in at the same wales in successive courses, and also that the weft-thread may be introduced either in every course or only in separated 110 courses, as desired.

Having thus described my invention, I claim and desire to secure by Letters Patent—

1. The combination in a rib-knitting machine, of the two needle-carriers each provided with needles, cams for actuating the needles so as to cause them to form stitches, means for separating the needles of one of said carriers, and provision for laying a weft-thread between said separated needles and behind the needles of the other carrier whereby it will be disposed alternately to one side and to the other side of the stitches on the needles of one carrier and wholly behind the 130 stitches on the needles of the other carrier.

2. The combination in a rib-knitting machine, of the two needle-carriers each provided with needles, cams for actuating the

needles so as to cause them to form stitches, means for moving the needles outwardly from one needle-carrier and back again to the same, and provision for feeding a weft-thread behind said needles when they are projected and at the same time feeding it behind the needles of the other needle-carrier.

3. The combination in a rib-knitting machine, of a circular needle-cylinder and a circular needle-dial both provided with needles, cams whereby the needles are actuated so as to cause them to form stitches, a circular plate located beyond said needle-dial and constructed for the reception and guidance of needles therefrom, means for moving needles from the circular needle-dial to said circular plate and back again, and provision for laying a weft behind said dial-needles when they are projected, and at the same time laying it behind the needles of the cylinder.

4. The combination in a rib-knitting machine, of two needle-carriers each provided with needles, cams for actuating the needles so as to cause them to form stitches, mechanism for moving alternate needles or sets of needles outwardly from one of the needle-carriers, and back again onto the same, and provision for laying a weft-thread behind the projected needles and at the same time laying it behind the needles of the other carrier.

5. The combination in a rib-knitting machine, of two needle-carriers each provided with needles, cams for actuating the needles so as to cause them to form stitches, means whereby in knitting one course certain needles are projected from one of the needle-carriers and then back again onto the same, and in knitting a succeeding course the alternate needles are thus projected and retracted, and provision for laying a weft-thread behind the projected needles and at the same time laying it behind the needles of the other carrier.

6. The combination in a rib-knitting machine, of two needle-carriers each provided with needles, cams for actuating said needles so as to cause them to form stitches, cams for projecting the needles of one carrier outwardly therefrom, jacks guided in the needle-grooves and serving to move the needles into range of said projecting-cam, cams for actuating said jacks, and provision for laying a weft-thread behind the projected needles and at the same time laying it behind the needles of the other carrier.

7. The combination in a rib-knitting machine, of two needle-carriers each provided

with needles, cams for actuating the needles so as to cause them to form stitches, a needle-receiving plate located beyond one of said carriers, means for projecting needles from said carrier onto the plate, jacks guided in the needle-grooves of the plate and serving to restore the needles to the carrier, cams for acting upon said jacks, and provision for laying a weft-thread behind the projected needles and at the same time laying it behind the needles of the other carrier.

8. The combination in a rib-knitting machine, of two needle-carriers each provided with needles, cams for actuating the needles so as to form stitches, a cam whereby the needles of one carrier may be projected beyond the same, two sets of jacks alternating with each other and guided in the needle-grooves of said carrier, cams, one for acting upon the jacks of one set and the other for acting upon the jacks of the other set, a plate located beyond the needle-carrier from which the needles are projected, said plate serving to receive the projected needles, means for restoring the needles from said plate to the carrier, and provision for laying a weft-thread behind the projected needles, and at the same time laying it behind the needles of the other carrier.

9. The combination in a rib-knitting machine, of two needle-carriers each provided with needles, cams for actuating the needles so as to form stitches, a cam adapted to project needles from one of the cam-carriers, said cam having an eye for guiding a weft-thread behind the projected needles and at the same time laying it behind the needles of the other carrier, and means for restoring the needles to the carrier after the weft-thread has been laid behind them.

10. The combination in a rib-knitting machine, of two needle-carriers each provided with needles, cams for actuating the needles so as to form stitches, a cam for projecting needles from one of the carriers, said cam having a heel for retracting the non-projected needles, means for restoring the projected needles to the carrier, and provision for laying a weft-thread behind the projected needles and at the same time laying it behind the needles of the other carrier.

In testimony whereof I have signed my name to this specification in the presence of two subscribing witnesses.

ROBERT W. SCOTT.
